(57) **CLAIM**

The ornamental design for angle corner connector for photovoltaic module frame, as shown and described.

DESCRIPTION

FIG. 1 is a perspective view of an angle corner connector for photovoltaic module frame showing our new design; FIG. 2 is a rear perspective view from the left thereof; FIG. 3 is a top plan view thereof; FIG. 4 is a front plan view thereof; FIG. 5 is a rear plan view thereof; FIG. 6 is a right plan view thereof; FIG. 7 is a left plan view thereof; and, FIG. 8 is a bottom plan view thereof.

1 Claim, 3 Drawing Sheets
